UNITED STATES PATENT OFFICE.

WILLIAM L. HEBERLING AND HENRY HEBERLING, OF HAVANA, ILLINOIS.

METAL ROOFING.

SPECIFICATION forming part of Letters Patent No. 468,015, dated February 2, 1892.

Application filed April 17, 1890. Serial No. 348,421. (No model.)

To all whom it may concern:

Be it known that we, WILLIAM L. HEBERLING and HENRY HEBERLING, citizens of the United States, residing at Havana, in the county of 5 Mason and State of Illinois, have invented certain new and useful Improvements in Metal Roofing; and we do hereby declare the following to be a full, clear, and exact description of the invention, such as will enable others skilled in the art to which it appertains to 10 make and use the same, reference being had to the accompanying drawings, and to letters or figures of reference marked thereon, which 15 form a part of this specification.

15 Our invention relates to metal roofing, particularly to a standing-seam roofing in which one edge of each sheet is flanged up and folded once, and only once, over the flanged edge of an adjoining sheet to complete the 20 seam.

The object of our invention is to provide a roof of this kind which, with proper tools, can be formed much more easily, rapidly, and cheaply than any other now known.

25 We accomplish our object in a very simple way, which will be better understood by reference to the accompanying drawings, in which like parts have like signs.

Figure 1 is a section of our roofing with 30 seams in different stages of completion. Fig. 2 shows our anchor as applied to the roof. Fig. 3 shows a reverse view of the finished seam 7. Fig. 4 shows a modified form of our roofing.

35 We first flange the sides of our main sheets, as seen in Fig. 1, turning the flange *a* about one and five-eighths inches high and the flange *b* about one inch high. We then cleat down the taller flange *a*, as shown at 5, Fig. 40 1, using a cleat with a long hook, as *c*, Fig. 2. When the taller flange is thus cleated down, the lower flange *b* is brought in position, as at 6, Fig. 1; and the flange *a*, with its cleats *c*, is then folded over the flange *b* and brought 45 down tightly to complete the seam, as at 7, Fig. 1.

In the reverse view of the finished seam 7 (shown in Fig. 3) it will be seen that the overlapping ends of the cleats *c* are closed

down snugly against the side of the seam. 50 We accomplish this by folding the top of the flange over with a tool which clamps and holds the ends of the cleats firmly against the seam during the operation. If desired, the flange *b* may be made high enough to have a 55 narrow portion of its top folded over with the flange *a*, which requires no extra labor and but little more material, as in Fig. 4.

The advantages of the method we have here described are its great rapidity and economy, 60 combined with perfect efficiency.

What we claim as new, and desire to secure by Letters Patent, is—

1. A roof-anchor having a straight body, with a base at right angles to one side and an 65 extension from its upper portion reaching down along its opposite side past its center, combined with a roofing-sheet having a perpendicularly-flanged edge embraced by said extensions down past its middle portion and 70 folded but once over an adjoining flange to form a standing seam.

2. A standing seam consisting of one or more roof-anchors, combined with two roofing-sheets, one of which has a flanged edge 75 embraced by said anchors and folded with them but once over the flanged edge of the other sheet, which rests on the base of the anchors, whose embracing ends extend from under the edge of the folded flange back over 80 the crown of the seam.

3. In combination, in a standing seam, the flange *a*, cleats *c*, and flange *b*, the flange *b* resting on the cleats *c*, the cleats *c* and flange *a* being folded once over the flange *b* and the ends of 85 the cleats extending from under the edge of the flange *a* back over the crown of the seam and partly down that side of it which is farthest from the base of the cleats, substantially as shown and described. 90

In testimony whereof we affix our signatures in presence of two witnesses.

WILLIAM L. HEBERLING.
HENRY HEBERLING.

Witnesses:

P. F. WARNER,
H. A. WRIGHT.
